UNITED STATES PATENT OFFICE.

CHARLES ROBERT STENBERG, OF GENOA, NEBRASKA.

SUPPORT FOR HEAD SETS.

Application filed June 21, 1924. Serial No. 721,444.

To all whom it may concern:

Be it known that I, CHARLES R. STENBERG, a citizen of the United States, residing at Genoa, in the county of Nance and State of Nebraska, have invented a new and useful 5 Support for Head Sets, of which the following is a specification.

This invention relates to head-sets for radio receiving instruments and the like, 10 and especially to means for supporting the ear pieces.

One of the chief objections to the head-sets now commonly used is the considerable pressure exerted against the ears, which 15 often causes great annoyance, pain and even injury to the user.

The general object of the present invention is to provide an improved support, which is simple and inexpensive in its construction, adapted to support for vertical 20 adjustment any of the ear pieces now used, and which may be so adjusted as to lessen or entirely remove the pressure from both ears or from one ear only.

25 The nature of the invention and its advantages will be apparent from the following detailed description taken in connection with the accompanying drawing, which illustrates the invention in its preferred form.

In the drawing:

Figure 1 is a front view of the invention, partly in elevation and partly in section.

Figure 2 is a side elevation of one side of 35 a head set having my invention applied thereto.

Figure 3 is a perspective detail view of the block for supporting the ear piece and the parts associated therewith.

40 Figure 4 is a detail view of the pressure plate and brackets between which the block is mounted.

The invention is adapted to be applied to a head-set having a head band composed of one or more resilient bowed members 10, 45 adapted to span the head of the user. A pressure plate 11 is secured at each end of the band, and is preferably provided with a lining 12 of felt or the like, although the lining is not essential to the invention. As 50 shown in the drawing, the plate 11 is provided with a number of holes 13 to which the lining may be secured by sewing, as indicated at 14. A pair of brackets 15 and 16 are riveted or otherwise secured to the outer side of each plate 11 in spaced relation to 55 each other, and one of the brackets, as 16, is

provided with a boss 17, internally threaded to receive the threaded end 18 of a thumb screw 19. A supporting block 20 is pivotally mounted at its inner end on the screw 19 between the opposed faces of the brackets 15 and 16, and the thumb screw 19 is formed with a shoulder 21 engaging the outer face of the bracket 15. Either the brackets or the pressure plate 11, or both, are somewhat 60 resilient, so that by tightening the thumb screw 19, the opposed bracket arms may be drawn together into clamping relation to the block 20 to secure the same in any position to which it may be adjusted.

Each ear piece 22 is pivotally supported in a yoke 23, provided with an upwardly extending stem 24. Each block 20 is provided with a bore 25 in which the stem 24 is vertically adjustable. A set screw 26, or other suitable means, may be provided by means of which the stem 24 may be readily secured in its adjusted position. The upper end of the stem 24 will ordinarily be provided with a knob 27, which may be detached for removing the stem 24 from the member or inserting it therein.

In the use of the head set, the same is retained upon the head by the pressure of the plates 11 against the head above the ears, and the supporting blocks 20 may be independently adjusted about the thumb screw 19 as an axis, so that either one of the ear pieces 22 may be held against the ear with as much or as little pressure as may be convenient. The stems 24 may be adjusted vertically in the bores 25 to bring the ear pieces at the proper height to secure the best results.

The invention is adapted to be attached to any head-set now in use. In most of these head-sets the ear piece is supported by a stem, and to apply the invention thereto, it is only necessary to remove the knobs 27. The invention is simple in its construction and consists of a minimum number of parts, which may be manufactured at a small expense. The ear pieces may be adjusted to any pressure, and positively held in such position merely by turning the thumb screws 19.

While I have shown in detail one embodiment of the invention, it is obvious that various modifications may be made in the form, size, proportion and arrangement of the various parts without departing from the salient features of the invention, or sacrificing any of its advantages. It is my

desire, therefore, to include all such modifications within the scope of the appended claims.

What is claimed is:

5. 1. In a support of the character described, the combination of a head band having a pressure plate secured to each end thereof, a block mounted for pivotal adjustment about an axis substantially parallel to each 10 plate, clamping means for securing the block in its adjusted position, said block having a bore extending from top to bottom thereof, and means cooperating with said bore for adjustably securing the stem of an ear 15 piece.
2. In a support of the character described, the combination of a head band having a

pressure plate at each end thereof, a pair of angle brackets secured to the outer face of each pressure plate and having opposed clamping surfaces which are substantially perpendicular to the pressure plate, a screw traversing the opposed portions of the brackets, a block pivoted on the screw, the latter being operable to clamp the block 25 between the brackets in any position to which it may be adjusted, said block having a bore extending from top to bottom thereof for receiving the stem of an ear piece, and means cooperating with said bore for adjustably securing said stem.

In testimony, that I claim the foregoing as my own, I have hereto affixed my signature.

CHARLES ROBERT STENBERG.
